UNITED STATES PATENT OFFICE.

EDGAR H. CLARK, OF RICHMOND HILL, NEW YORK, ASSIGNOR TO WESTERN ELECTRIC COMPANY, INCORPORATED, OF NEW YORK, N. Y., A CORPORATION OF NEW YORK.

TELEPHONE SYSTEM.

Application filed December 21, 1922. Serial No. 608,139.

This invention relates to telephone systems and particularly to coordinate switching apparatus.

- It is the object of this invention to evenly distribute traffic over a plurality of common connecting links by the use of apparatus which is characterized by its simplicity of construction and its speed, economy and reliability of operation.
- 10 Heretofore, in such systems as that disclosed in the British Patent No. 183,438, issued to Western Electric Company, Limited, accepted September 6, 1923, it has been proposed to assign a group of link circuits to a plurality of subscribers' lines and to arrange the intermediate apparatus in such a manner as to direct all incoming calls to the link circuit electrically nearest the incoming lines, and when such link is found 15 busy, to automatically transfer the call to the next succeeding link. It is apparent in such a system that the link circuits electrically nearest the incoming subscribers' lines will be called upon to handle the bulk 20 of the traffic assigned to the group in which they are located, and that the link circuits electrically farthest from the incoming subscriber's line will remain relatively inactive.
- 25 From the foregoing, it is evident that in such a system, the wear on a link circuit in a group varies directly with its electrical proximity to its associated incoming subscribers' lines. This uneven wearing effect 30 will necessitate frequent repairing and adjusting of the link circuits electrically nearest the lines incoming to their respective groups.

- 35 The foregoing object of this invention is obtained by the provision of a separate starting conductor for each line and a relay for each group of links for connecting each of said starting conductors to a different one of said links from whence the selection of an 40 idle link by said lines may proceed.

- 45 Other features and advantages as are contemplated by the present invention will be clearly understood from the following detailed description and by reference to the 50 accompanying drawings, in which Fig. 1 shows two groups of incoming lines with their respective distributing link relays; Fig. 2 shows two groups of link circuits adapted to interconnect the lines incoming

from the groups shown in Fig. 1 to the outgoing trunk circuits shown on the right of Fig. 2.

55 The following description is directed only to the operation of the circuits employed in switches of this type, but a clear understanding of the type of mechanical apparatus which may be employed in connection with these circuits may be had from the above mentioned British Patent No. 183,438 of 60 1923.

65 Considering the combined circuit arrangement shown in Figs. 1 and 2 the operation is as follows:

70 There are shown two groups of two incoming lines each, the upper group containing lines 20 and 21, and the lower group containing lines 22 and 23.

75 Let it be assumed that the subscriber on line 21 wishes to establish a connection. The following description will show how, upon the removal of the receiver on line 21, the line will be automatically connected to trunk 100.

80 The calling subscriber on line 21 removes the receiver from the switchhook and establishes a circuit for the energization of line relay 24. This circuit extends from grounded battery, left-hand winding of relay 24, back contact and outer armature of cut-off relay 25 over the closed loop of line 85 21, the inner armature and back contact of relay 25 and thence to ground through the right-hand winding of line relay 24. The operation of relay 24 establishes a circuit from grounded battery, winding of vertical line magnet 28, conductor 29, armature and front contact of line relay 24, winding of relay 26, normal make-before-break contacts of relay 26, conductor 27, conductor 30, back contact and upper armature of 90 relay 31, conductor 32 to ground over the back contact and upper armature of relay 33. Relay 26 energizes in this circuit and in attracting its armature establishes a circuit which may be traced from grounded 100 battery, winding of vertical line magnet 28, conductor 29, armature and front contact of line relay 24, winding of relay 26, front contact and armature of relay 26, conductor 34, winding of relay 31, conductor 32 to ground over the back contact and upper armature of relay 33. Relay 31 operates in this circuit and at its upper armature interrupts the 105

original energizing circuit for relay 26 and at its lower armature establishes an obvious circuit for the distributing link relay 35. The operation of magnet 28 in the circuit 5 previously traced rotates its associated line bar and prepares for operation the insulating pieces such as 36 shown in the vertical line above magnet 28. Magnet 28 in attracting its armature closes a circuit from 10 ground, front contact and inner left-hand armature of magnet 28, conductors 37 and 38, back contact and outer left-hand armature of slow releasing relay 39, winding of trunk bar magnet 40 to battery and 15 ground.

Magnet 40 causes the rotation of its associated trunk bar and prepares for operation the insulating pieces such as 41 common to the trunk bar and respectively individual to the several links. Magnet 40 in operating establishes a locking circuit for itself which extends from grounded battery, winding of magnet 40, inner armature and back contact of relay 42, front 20 contact and innermost armature of magnet 40, conductor 37 to ground over the inner left-hand armature and front contact of magnet 28. This locking circuit is necessary owing to the fact that upon the energization of magnet 40, a circuit is established from ground, middle armature and front contact of magnet 40 to battery and ground through the winding of slow releasing relay 39 causing the operation of this 25 relay and the opening of the original energizing circuit for magnet 40.

The operation of distributing link relay 35, as described, as a consequence of the operation of line relay 24, causes the attraction 30 of its armatures, thereby connecting the windings of the individual link magnets 43, 44, 45 and 46 to the conductors 47, 48, 49 and 50, respectively, which in turn are adapted to extend these connections to 35 ground at the outer left-hand armature of magnet 40 subsequent to the actuation of their respective associated line bar magnets such as 28, 51 and 52.

Magnet 28 having been operated upon the 40 actuation of line relay 24 completes a circuit extending from ground, outer left-hand armature and front contact of magnet 40, conductor 53, outer left-hand armature and front contact of magnet 28, conductor 47, 45 lowermost armature and front contact of distributing link relay 35, armature and back contact of relay 54, conductor 55 and thence to battery and ground through the winding of individual link magnet 43. 50 Magnet 43 becomes energized in this circuit and causes the movement of the cards 36 and 41 which, as hereinbefore described, have been conditioned for operation by the actuation of the vertical magnets 28 and 40, 55 respectively. The actuation of the cards 36

and 41 effects the establishment of a circuit from the line conductors 56, 57 and 58 leading from station 21 through the link conductors 59, 60 and 61, respectively, to the trunk conductors 62, 63 and 64, respectively. A circuit is now established from ground, front contact and right-hand armature of slow releasing relay 39, through conductor 64, link conductor 61, line conductor 58 to battery and ground through 70 the winding of cut-off relay 25. A circuit may also be traced from ground on link conductor 61 over conductor 65, winding of relay 54, conductor 55 through the winding of individual links magnet 43 to battery 75 and ground, this circuit forming a means for maintaining magnet 43 operated during the use of the talking circuit. Relay 54, however, does not become immediately energized in this circuit due to the fact that its winding is short circuited by the extension of ground from the armature of the trunk bar magnet as hereinbefore described.

Upon the energization of cut-off relay 25, line relay 24 becomes deenergized, resulting 80 in the deenergization of relays 26, 31 and 35 and magnet 28, whereupon the short circuit about the winding of relay 54 being removed this relay becomes energized and transfers the control of conductor 47 from 85 magnet 43 to magnet 44.

As soon as the line 21 is extended through to the trunk 100 a circuit through winding of relay 42 is completed over the substation 100 loop and this relay remains energized during the establishment of the connection. Relay 42 opens the locking circuit for magnet 40 which releases a switch bar associated therewith. Relay 42 also maintains 105 relay 39 operated by placing a ground on the winding of relay 39 as a substitute for the original ground placed there by the middle armature of magnet 40. The connection between line 21 and trunk 100 is maintained by the continued energization of 110 relay 39 which controls the link bar serving the link 101.

When the subscriber on line 21 replaces his receiver on the switchhook and opens the loop of this line, relay 42 becomes deenergized and shortly thereafter relay 39 retracts its armatures removing ground from conductor 64, allowing magnet 43, relay 54 and cut-off relay 25 to become deenergized, whereupon the connections are 115 restored to normal.

When trunk 100 is found busy relay 39 is energized so that a second call initiated in any subgroup of lines will seize trunk 105 through a circuit extending through the 120 innermost armature and back contact of magnet 40, inner left-hand armature and front contact of relay 39, back contact and outer left-hand armature of relay 75 to battery and ground through the winding of 125 130

magnet 76. The magnet 76 functions in a manner similar to magnet 40 as hereinbefore described.

It is to be noted that when relay 54 is energized in the locking circuit for magnet 43 in the connection just described a call emanating from line 20 which would effect the operation of the vertical line magnet 70 would be handled over conductor 47 as before but the circuit for magnet 43 would be found open at the back contact of relay 54 whereupon the connection would be transferred to link 102 by the energization of magnet 44 over the armature and front contact of relay 54 and armature and back contact of relay 90. It is to be further apprehended from the disclosure that calls emanating from stations 20 and 21 having access to vertical line magnets 28 and 70 will normally be handled over the link circuit 101. Furthermore, calls emanating from stations having the line relays 91 and 92 having access to magnets 51 and 93, will normally be handled over link 102, and calls originating from the station having line relay 94, having access to the vertical line magnet 52 will normally be handled over link 103. The same procedure will apply in handling calls over the other various links in the group, and is also applicable to the lower group of links shown in Fig. 2.

By giving preference to the various lines in a group for a selection of a link circuit over which to complete a connection, it is evident that no one link will be called upon to handle each call incoming from the stations served by a group including this link, but that the traffic will be distributed substantially evenly over the various links in the group.

Some of the general features of this system which are included in the aforesaid British patent are: First, the lines in a vertical or longitudinal row above magnet 28 form one digital subgroup, and, second, the lines in a horizontal or transverse row to the right of the group of magnets 43 to 46 form another digital subgroup. These subgroups may be said to be in the two principal directions of a two coordinate system, and, hence, in a one-hundred line main group there will be twenty digital subgroups, ten of which will be characterized by a tens digit, and the remaining ten will be characterized by a units digit.

All the link circuits have access to the trunks such as 100 and 105. The link circuits are, however, divided into groups and each group of link circuits is individual to a particular group of lines in one direction of the two coordinate system, thus the group of link circuits including links 101, 102, 103 and 104, is individual to the particular group containing lines 20 and 21, etc. and forms a row of contact sets, one before each line and trunk

bar. It should be noted, however, that each of these links though available to each of these lines is initially assigned to certain lines in each group, for instance, the link 103 is initially assigned to calls emanating from the station associated with line relay 94, that is, a call originating at this station will be handled over the link 103 whenever this link is idle instead of first testing the links 101 and 102 for their idle or busy condition.

It should be further noted that magnet 28 upon energizing opens its outer right-hand armature contacts and removes battery potential from the winding of all other magnets corresponding to magnet 28, such as magnets 70, 51, 93 and 52, etc., serving other lines of the same or other subgroups, as for example, lines 20 and 22 so that should a call be simultaneously initiated upon another line served by such other magnets, no interference will result, and the possibility of double connections to the same link circuit is obviated. In like manner the remaining magnets 70, 51, 93, etc., disconnect battery from all other magnets succeeding them in order in such a manner, that it is not possible for two such magnets to become energized at the same time, the magnet nearest the source of potential being given the preference.

If two lines in different groups, for example, lines 21 and 23 both served by the same magnet 28 call simultaneously, the connection of both lines to the same trunk circuit through different link circuits is prevented since it is not possible for link bar magnets such as 43 and 95 serving respectively the groups of lines in which lines 21 and 23 terminate to become simultaneously operated. The simultaneous operations of magnets 43 and 95 during the operation of trunk bar magnet 40 (such operations would permit lines 21 and 23 to be simultaneously connected to trunk 100) are prevented by the operation of relay 33 which at its upper armature opens the initial energizing circuit for relay 26 which controls the operation of relay 31. Thus if lines 21 and 23 simultaneously initiate calls, line 23 will have the preference, but if line 21 initiates a call just a small fraction of a second prior to line 23, relay 31 will have become operated and will have opened the initial energizing circuit of relay 98.

From the foregoing description it is obvious that the circuit arrangement disclosed herein provides for a substantially even distribution of calls over the various link circuits in a group, and figuring on the basis that the calls to be handled over a group of link circuits will emanate from the various stations assigned to the group of links substantially in rotation the distribution of link circuits will be even.

What is claimed is:

- 4
1. In a telephone system, a plurality of lines, a group of link circuits, a relay common to all of said lines, a plurality of contacts controlled by said relay, each of said contacts being individual to one of said lines, and a relay for each of said lines adapted to include its associated contact in a circuit to select one of said link circuits for cooperation with one of said lines subsequent to the operation of said first relay.
  2. In a telephone system, a group of lines divided into sub-groups, a group of link circuits, a line magnet for each line in a sub-group, a relay common to all links in a group and having a plurality of contacts controlled thereby, each of said contacts being individual to a sub-group of lines and to a link circuit in said group, and means effective upon the conjoint operation of one of said line magnets and said relay for connecting the line associated with the operated line magnet to the link circuit corresponding to the contact individual to the sub-group of lines in which said line is located.
  3. The combination with a plurality of groups of line extending links of a plurality of conductors equal in number to the links in said groups, a relay individual to each of said groups for extending said conductors into operative relation with said groups, each of said conductors being arranged to normally control a particular one of said links, and means for transferring the control of each of said conductors to the other links of the group.
  4. The combination with a plurality of groups of line extending links of a plurality of conductors equal in number to the links in each of said groups, a plurality of lines, operating means for each of said lines associated with said conductors, means individual to each of said groups for extending said conductors into operative relation with said groups, each of said conductors being arranged to normally control a particular one of said links, means effective upon the joint operation of one of said operating means and last mentioned means for connecting one of said lines to a preselected link, and means for transferring the connection to the other links in a group.
  5. The combination with a plurality of groups of line extending links of an advanced starter wire circuit for each of said groups, a plurality of conductors common to said groups for entering and controlling said starter wire circuit at various points thereof, and means individual to each of said groups for operatively associating said conductors with said starter wire circuit.
  6. The combination in a switching system of a plurality of lines, operating means for said lines, a group of link circuits, operating means for each link in said group, a plurality of conductors, one for each of said
  - link circuits, and means for connecting each of said conductors into operative relation with its respective link circuit and adapted to cooperate with said first operating means in effecting the operation of said second operating means to effect the connection of one of said lines with a certain one of said link circuits.
  7. The combination in a switching system of a plurality of lines, operating means for said lines, a group of link circuits, operating means for each link in said group, a plurality of conductors, one for each of said link circuits and a relay controlling a plurality of contacts for connecting each of said conductors into operative relation with its respective link circuit and adapted to cooperate with said first operating means in effecting the operation of said second operating means to effect the connection of one of said lines with a certain one of said link circuits.
  8. The combination in a switching system of a plurality of lines, operating means for said lines, a group of link circuits, operating means for each link in said group, a plurality of conductors, one for each of said link circuits, means for connecting each of said conductors into operative relation with its respective link circuit and adapted to cooperate with said first operating means in effecting the operation of said second operating means to effect the connection of one of said lines with a certain of said link circuits, and means for transferring the connection to the other link circuits in the group.
  9. In a telephone system, a plurality of groups of lines, and a plurality of groups of link circuits, each of said groups of link circuits serving a corresponding group of lines, each of said links being normally assigned to one of said lines, and each line in each group having preference to a different link in its corresponding group of link circuits, and all of said links in each group being successively accessible to each line in its corresponding group of lines.
  10. In a telephone system, the combination of a plurality of incoming lines, a switch having a group of link circuits, each of said links being normally assigned to one of said lines, a plurality of contact sets for each of said link circuits, switching members cooperating with each other, each switching member serving a plurality of contact sets, means for operating said switching members, and means for connecting one of said lines with its normally assigned link circuit and transferring the connection successively to the succeeding links in said group when the normally assigned link is busy, subsequent to the actuation of said first mentioned means.
  11. In a telephone system, lines, a switch

having links for extending said lines, a conductor for each of said lines, a chain-starting circuit for said links, and a single relay for connecting said conductors to different points in said chain-starting circuit from whence the selection of an idle link may proceed.

12. In a telephone system, lines, groups of links for extending said lines, a conductor for each of said lines, a chain-starting circuit for each group of links, and a relay

for each group of links for connecting each of said conductors to a different point in the chain-starting circuit of the group of links associated with said relay from whence the 15 selection of an idle link in each group may proceed.

In witness whereof, I hereunto subscribe my name this 18th day of December, A. D. 1922.

EDGAR H. CLARK.
